UNITED STATES PATENT OFFICE.

LOUIS W. DOWNES, OF PROVIDENCE, RHODE ISLAND.

OIL-FUSE.

1,203,316.

Specification of Letters Patent. Patented Oct. 31, 1916.

Application filed July 17, 1912, Serial No. 710,044. Renewed February 26, 1914. Serial No. 821,318.

To all whom it may concern:

Be it known that I, LOUIS W. DOWNES, of Providence, Rhode Island, have invented a new and useful Improvement in Oil-Fuses, which invention is fully set forth in the following specification.

Experience has demonstrated that electric fuses of well-known types which have heretofore given satisfactory operation on single phase high tension circuits are not always sure and satisfactory in their operation on the more modern poly-phase systems of electric distribution, and hence with such modern systems have come to be regarded as a source of uncertainty and consequent danger.

The principal object of the present invention is to provide an electric fuse adapted to serve as a primary and junction cut-out on high tension poly-phase circuits such as those of 2,500 bolts or more. That object I believe I have attained by the fuse of the present invention which in its operation is adapted to break the circuit in oil, tests and experience with such fuses having yielded satisfactory results under conditions of extreme severity and heavy overload.

A further object of the invention is to provide a structure which will prevent the oil in the receptacle or casing from being blown out of said casing under conditions that may be frequently encountered, such discharge or absence of the oil leaving nothing in the casing to extinguish the arc that might be formed, as the result of which there would be violent arcing with consequent destruction of or injury to the device.

To illustrate, a condition might exist on a circuit supplying lights or power whereby the lines had become short circuited at some distant point, causing immediate blowing of the fuse at the transformer. A lineman going to investigate the trouble might not immediately find the cause and proceed to insert a new fuse. In the absence of provision to meet the condition, the instant the new fuse is inserted and its connection in the circuit effected—the trouble still being present—it would be blown by a heavy rush of current through it, and if the cover of the receptacle had not been closed and securely fastened, it would be forced off and a considerable part of the oil immediately blown out of the casing, with the result that dangerous arcing would take place. To meet such conditions the fuse of my present

invention embodies means whereby the cover of the casing must be closed and locked before the newly inserted fuse can be connected between the circuit terminals within the 60 casing. As a suitable way of providing for such closing and locking of the cover before the circuit is completed through the fuse, I have illustrated the employment of a bayonet joint construction to be more fully described in detail hereafter. By such construction and the relative arrangement of the fixed terminals within the casing and the contacts on the fuse carrier between which the fuse link is connected, the casing 70 cover with the carrier fixed thereto must be put in place and then rotated through an arc, preferably of approximately 90°, before the contacts on the fuse carrier engage the fixed terminals within the casing to 75 complete the circuit through the fuse link. Hence, even if a new a fuse be inserted in a live circuit—one for instance which has been crossed by another circuit—no harm can occur to the apparatus or the operator since 80 there is no opportunity for the oil to be blown out. Preferably the oil level is somewhat below the top of the oil chamber in the casing to permit of movement of the oil on the blowing of the fuse. Experience has 85 demonstrated that when such a fuse is blown under very severe conditions the oil will be driven up against the top of the box with considerable force, but will immediately fall back to the bottom of the casing, any arc 90 that may be formed being promptly extinguished and burning of the fuse terminals thus avoided.

In the accompanying drawing illustrating what is now regarded as a preferred embodiment of the invention, Figure 1 is a vertical section on line 1—1 of Fig. 2. Fig. 2 is a horizontal section on line 2—2 of Fig. 1. Fig. 3 is a vertical section on line 3—3 of Fig. 2. Fig. 4 is a horizontal section on 100 line 4—4 of Fig. 1. Fig. 5 is a fragmentary view of the fuse carrier and parts thereon. Fig. 6 is a detail sectional view on line 6 of Fig. 2. Fig. 7 is a detail sectional view on line 7 of Fig. 2. Fig. 8 is a detail view 105 of one of the fuse carrier contacts. Fig. 9 is a detail view of the fuse link of Figs. 1—5. Fig. 10 is a detail view of another form of fuse link. Fig. 11 illustrates the fuse link of Fig. 10 applied to a fuse carrier 110 shown in outline, and Fig. 12 is a view similar to Fig. 11 but showing the action

of the fuse link when disrupted by excessive current.

20 is a cup-like casing, preferably of cast metal, having at one side a flat plate or flange 21 for fastening the device to a wall or other structure. Terminal conductors 22 and 23 enter said casing by passing upward through bushings 24, 25, respectively. The conductors make a close fit through the 10 bushings the openings of which are enlarged at the upper end and filled with a suitable oil proof cement 24' such as shellac gum poured in while liquid. This seals the cable entrances and prevents escape of oil from 15 the casing at these points. The bushings are of porcelain or other suitable insulating material and depend through vertical openings in bulges or pockets 26, 27 at opposite sides of the casing. Vertical flanges or ribs 28 20 positioned at intervals about the exterior surface of the casing serve in the well known way to extend the heat radiating surface and thereby facilitate dissipation of the heat developed by the fuse when running 25 under normal conditions of load. The casing is made relatively large to contain a liberal volume of oil and dissipation of heat is such as to avoid any possibility of disintegration of the oil and insure a safely low 30 temperature under normal working conditions.

On the inside of the casing the terminal conductors 22 and 23 lead to fixed spring terminals adapted to coöperate with contacts on the fuse carrier as described hereafter. The inner end of conductor 22 is soldered or otherwise electrically connected in a clip 29 which makes electrical contact with one end of a U-shape terminal 30, the 40 other end of which is broadened and shaped in the form of a shoe 31 adapted to bear against the peripheral surface of the fuse carrier and when the latter is rotated to proper position to make electrical contact with one of two contact pieces thereon. Both the clip 29 and the terminal 30 are secured to and supported from the quarter circle arc-shaped block 32 of porcelain or 45 other suitable insulating material by screws 37, 38, said block 32 resting at its opposite ends upon shoulders 33, 34 and being secured to said shoulders by screws 35. Between the shoulders the block 32 bridges a recess or pocket 36 into which the terminal 50 30 depends. Inside of the casing the terminal cable 23 leads to similar parts, the description of which need not be here repeated and to which the reference numerals heretofore mentioned also apply.

60 The casing is partially closed by ring 39 with interposed gasket 40 and held in place by four screws 41.

42 is a cover fitting closely in the central opening of ring 39 and having a flange 65 depending about an upwardly projecting

flange on said ring 39; an interposed gasket 43 of cork or other suitable material insures a tight joint and yields sufficiently to permit the making of a bayonet joint connection between the cover and the ring 39 about to 70 be described. Notches 44, 44, (Fig. 4) at opposite sides of the central opening through ring 39 admit of the passage of lugs 45, 45 on the lower edge of the cover 42 until such lugs clear the lower edge of the ring 39, 75 whereupon the cover may be rotated to carry the lugs 45 out of register with the notches 44 into locking engagement with the under edge of the ring 39, the parts described thus constituting a bayonet joint. The cover is 80 preferably of cast metal hollowed with a depending stud adapted to fit into a central opening in the upper end of a fuse carrier 46, thus centering the latter with relation to the cover. A suitable cement 47 filled 85 into the cover about the upper end of the fuse carrier 46 in a plastic state thereafter hardens and securely fastens the fuse carrier to the cover.

The fuse carrier 46 is preferably of porcelain but may be of other suitable insulating material. On opposite sides of its lower end, it has vertical grooves or channels 48 enlarged at their upper ends to receive contacts and other parts about to be described. 90 One of these contacts, illustrated in detail in Fig. 8, consists of a plate 49 fitting against and held to an overhanging horizontal surface of the fuse carrier by means of screw-bolts 50 and 51 passing through openings 100 in said plate 49; a leg 52 of plate 49 has a rounded outer surface adapted to engage and make electrical contact with the shoe 31 of the terminal 30 when the cover and the fuse carrier have been rotated into position 105 to bring these parts into engagement. A second leg 53 of plate 49 bears against an upright surface of the carrier 46 and has an opening 54 traversed by a bolt 55 the head of which is secured in a recess in the fuse carrier by a filling of suitable cement adapted to be applied in a plastic state and to thereafter harden. A spring 56 fastened to the underside of plate 49 also has an opening traversed by the bolt 55, a knurled nut 57 110 making screw-threaded engagement with the bolt on the outer side of spring 56. This arrangement of parts is duplicated on opposite sides of the fuse carrier and the description thereof need not be repeated.

The fuse carrier of insulating material thus serves as a barrier or wall isolating the two sides of the circuit except for the fusible part of the link extending across the lower end of said carrier.

Two suitable forms of links or fuses for use in this device are that shown in Figs. 1, 5 and 9, and that shown in Figs. 10, 11 and 12. The construction of the former is as follows:—At opposite ends it has notched 130

copper terminals 60 to each of which there is riveted and soldered a copper wire section 61 each of which is in turn riveted and soldered to a short flat strip section 62, preferably of zinc. These strips 62 are slightly tapered at their opposing ends which are positioned to terminate a predetermined distance apart and are connected by a narrower metal strip 63, preferably of zinc, overlapping the strips 62, 62, and joined thereto by solder adapted to melt at a suitably low temperature. The zinc strips 62, 62 as thus connected by narrower zinc strip 63 constitute in effect an ordinary centrally notched flat fuse strip or link. As most clearly illustrated in Fig. 1 such fuse link is bent in U-shape around the fuse carrier 46 with the narrow zinc strip 63 and parts of the strips 62, 62, extending across the lower horizontal end of said carrier and the remaining portions of the link extending upward in the channels 48, 48, at opposite sides of the fuse carrier, the notched terminals 60, 60, each engaging its corresponding screw-bolt 55 between the leg 54 and the spring 56 and being tightly gripped between such parts by the tightening of the knurled nut 57. In case of excessive current traversing the fuse the temperature produced is such as to melt the solder connecting the strip 63 to the strips 62, 62, permitting said strip 63 to drop to the bottom of the casing 20, thereby opening the circuit. But in case of greatly excessive current, such temperature might be instantaneously developed as not only to melt the solder joining the strip 63 to the strips 62, 62, but also melt the strip 63.

The object of the before described construction of fuse link is to overcome difficulty experienced when using an ordinary notched link of zinc or other similar metal, that of excessive temperature rise in the oil which might ultimately change the characteristics of the oil. This difficulty might also be overcome by the use of a simple flat link of Figs. 10-12, when made up in the following manner:—Two copper or bronze terminal strips 70, 70 are notched for engagement with the two bolts 55, 55, previously mentioned, and joined by fusible connecting strip 71, the overlapping ends of the strips 70 and 71 being riveted and soldered together. Strip 71 is of some suitable low melting alloy, notched at its middle in the well-known manner for the purpose of giving the proper overload characteristics. The outer ends of terminals of this link being of bronze or copper and having a relatively lower resistance, are not heated excessively by the passage of the current through them, while the connecting strip 71, being of short length and low melting point, does not reach a very high temperature; it follows then that the total temperature rise in the oil is thus kept at a reasonably low figure. The

outer ends of the strips 70, 70, are bent as shown in Fig. 11, whereby the forcing of these bent ends to a straight position as illustrated in dotted lines in said Fig. 11 and their engagement with the bolts 55 between the plates 53 and the springs 56 places said strips 70 under a tension tending to cause the lower ends thereof to spring apart or separate. In operation when an overload softens the fusible strip 71 at its notch, the strips 70, 70 spring apart as illustrated in Fig. 12 quickly separating the severed ends of the strip 71, the action resembling that of a quick break switch submerged in oil and eliminating or minimizing any possible formation of an arc upon the opening of the fuse.

The casing is filled with some suitable oil such as paraffin or mineral oil, preferably to approximately the level, indicated by the line marked "Oil level" in Figs. 1 and 3, the action of such oil in preventing or suppressing the formation of an arc upon the blowing of the fuse being well-known. As has already been suggested, when the cover and the fuse carrier are inserted in the casing in such position as to pass the lugs 45 on the cover through the notches 44, the contacts 52, 52, on the fuse carrier stand in a line approximately transverse to the line of the terminal shoes 31, 31 and hence out of contact with the latter; and to bring these parts into engagement or electrical contact the cover must be rotated through an arc of approximately 90° which serves to carry the lugs 45 out of register with the notches 44 and hence into locking engagement with the under edge of the depending flange around the central opening through the ring 39. This insures locking of the cover in place before the electric circuit is established through the fuse link and its connections mounted on the fuse carrier 46. The action is reversed upon the removal of the cover 42 and the fuse carrier 46, and if at the time of such removal the fuse link has not been disrupted and the circuit is complete therethrough, the opening of the circuit will take place between the contacts 52 and the terminal shoes 31 both of which are at the time submerged in oil; consequently there will be no material arcing.

To relieve possible excessive pressure within the casing due to the formation of vapor when the fuse acts under excessive overcharge of current, a relief valve is provided. As shown it consists of a tube 75 threaded into an opening in the ring 39 and closed at its outer end by a plug 76. A stem 77 working through an opening in said plug carries at its outer end a cap 78 and at its inner end a piston 79. In the normal position, the piston closes vent openings 80 through the side of tube 75 and cap 78 fits down over the outer end of the tube, ex-

cessive pressure within the casing forces the piston outward and opens the vents for the escape of gas or vapors. The cap 78 is held in its lifted position by the friction of the 5 piston, thus serving as an indicator showing that the fuse has operated.

What I claim is:

1. The combination of a receptacle or casing containing a suitable arc suppressing liquid; circuit terminals within said receptacle; a cover and fuse-carrier for closing the receptacle; locking means for securing the cover in its closed position; contacts on the fuse-carrier adapted to engage the 10 terminals in the receptacle respectively, said contacts and terminals being so relatively arranged as to be capable of such engagement only while the cover is locked closed by said locking means; and a fuse-link connected between said contacts on the fuse carrier.
2. The combination of a receptacle or casing containing a suitable arc suppressing liquid; circuit terminals within said receptacle; a cover and fuse carrier for closing the receptacle; interlocking means on the cover and receptacle adapted to be engaged to secure the cover in place; contacts on said 15 fuse-carrier adapted to be engaged with the terminals respectively only by relative movement of the cover bringing the interlocking means into engagement in advance of the engagement of the contacts; and a fuse-link connected between said contacts on the fuse-carrier.
3. The combination of a receptacle or casing containing a suitable arc suppressing liquid; circuit terminals within said receptacle; a cover and fuse-carrier; a bayonet- 20 joint connection between the receptacle and cover for locking the latter closed; contacts positioned on said fuse-carrier to be engaged with the terminals respectively only by the relative rotation of the cover and receptacle serving to interlock the parts of the 25

bayonet-joint; and a fuse-link connected between said contacts on the fuse-carrier.

4. The combination of a receptacle or casing containing a suitable arc suppressing liquid; a cover for closing the top of the receptacle said cover having a carrier depending into the receptacle; interlocking means on the cover and receptacle adapted to be brought into engagement by relative rotation thereof; circuit terminals within the 30 receptacle; contacts on opposite sides of the carrier adapted to be engaged with the terminals by said relative rotation which engages the interlocking means; and a fuse link bending around the lower end of said 35 carrier and connecting between said contacts.

5. In an electric fuse, the combination of a fuse-link support, a fuse-link secured at two separated points to said support, said 40 link at one or both of said points of anchorage being normally bent but—in being secured to the support—caused to assume a more straightened position, thereby creating in the link a tension adapted upon rupture 45 of the link to relatively move away from each other the terminals formed by said rupture.

6. In an electric fuse, the combination of a fuse-link support, a fuse-link secured at 50 its ends to said support in an approximate U-shape, said link at one or both of its ends being normally bent but caused to assume a more straightened position in being secured to the support, thereby creating in the link 55 itself a tension adapted upon rupture of the link to relatively move away from each other the terminals formed by said rupture.

In testimony whereof I have signed this specification in the presence of two subscribing witnesses.

LOUIS W. DOWNES.
